UNITED STATES PATENT OFFICE.

WILHELM TRAUGOTT WIEGAND, OF NEW YORK, N. Y., ASSIGNOR TO
EIMER & AMEND, OF NEW YORK, N. Y.

STOP-COCK.

SPECIFICATION forming part of Letters Patent No. 764,322, dated July 5, 1904.

Application filed August 17, 1903. Serial No. 169,800. (No model.)

To all whom it may concern:

Be it known that I, WILHELM TRAUGOTT WIEGAND, a subject of the Emperor of Germany, and a resident of the borough of Manhattan, in the city, county, and State of New York, have invented certain new and useful Improvements in Stop-Cocks, of which the following is a specification.

This invention relates to stop-cocks for apparatus or receptacles—such, for instance, as burettes or measuring-tubes—used by analytical chemists in effecting chemical reactions and for other purposes, the leading features of novelty wherein may be summarized in the following manner: first, means providing an adjustable closure for a passage through a vessel in such manner that the independent closure member cannot become disconnected from said vessel; second, improved means whereby the regulation of such adjustable closure can be operated with increased facility and correctness.

In apparatus of the above-noted class an objectionable feature of the stoppering devices commonly employed resides in the liability of the usual tapered ground-glass cocks to accidentally fall out from their seats and become broken, thus rendering useless the entire apparatus.

It is the purpose of my invention to provide means overcoming this defect, and, furthermore, in conjunction with the provision of a turnable sleeve as the closure and regulating member for the fluid-passage I employ a radially-disposed handle whose concentric movement as communicated to said closure-sleeve affords an easily-operated means of positively regulating said closure.

The invention also includes the various novel features of construction and arrangements of parts, as will be fully described hereinafter and particularly pointed out in the claims.

In the drawings accompanying this application, Figure 1 is a vertical elevation of a duplex measuring-tube broken away, provided with means for controlling the flow of fluid from the upper to the lower portion thereof and from said lower portion and exteriorly

from said upper portion. The figure also shows an ordinary support for said tube. Fig. 2 is an enlarged detail sectional view showing the sleeve turned to open a passage past the partition in the tube. Fig. 3 is an enlarged detail sectional view showing the sleeve turned to open a passage to the exterior of the upper portion of the tube, and Fig. 4 is an enlarged detail sectional view of the lower closure shown in Fig. 1.

In said figures the letter A indicates the upper containing portion of a measuring-tube, which continues downwardly into a contracted channel *a* and thence gradually expands into a hollow, concentric, outwardly-tapering or truncated-cone-like formation *a'* to seat a correspondingly-shaped sleeve B, which is adapted to fit snugly thereabout. Within the hollow cone-like portion *a'* is formed a transverse partition or diaphragm, as *a''*, to separate the interior of the upper tubular portion A from the interior of the lower tubular portion C of the apparatus.

The sleeve B is provided with a radial arm *b*, which serves as a handle whereby said sleeve may be turned in the performance of its functions, which will be referred to hereinafter, and a vertical recess or groove *b'* is formed in the inner surface of the sleeve at the point where said sleeve is outwardly enlarged by the junction therewith of handle *b*.

Orifices *a'' a'*, formed through the wall of the cone-like portion *a'*, are located, respectively, above and below the partition *a''* and are arranged to lie both within the compass of the groove *b'* when the sleeve B is seated closely about the portion *a''* and is turned to register said groove *b'* with said orifices *a'' a'*. At such time the flow of fluid from the upper container A is permitted through orifice *a''*, groove *b'*, and orifice *a'* into the lower container C. The quantity of the flow may be regulated to a nicety by turning sleeve B with the aid of handle *b*, whereby the size of the inlet into passage *b'* is adjusted. In this manner the volume of fluid allowed to pass may be reduced infinitesimally or entirely cut off.

At another point in the radius of the sleeve B a spout or curved outlet-pipe, as D, extends

therefrom, the inner end of its passage being located in the same horizontal plane as the upper orifice α^2 when the sleeve B is seated about the cone-like portion α' . Hence it is obvious that upon the sleeve B being turned to register the passage in spout D with said orifice α^2 fluid is permitted to flow through said spout D to the exterior of the apparatus. By suitably turning the sleeve B the area of the spout-passage end exposed to the orifice α^2 may be duly regulated and may be reduced so as to permit fluid to pass slowly from the spout D in the form of drops.

As a means of indicating the position of the orifices α^2 α^1 I place an indicator, as a bead E, upon the portion α in perpendicular alinement with said orifices, whereby in order to register the groove β' with said orifices the handle b is turned until directly under said bead E, or when desired to employ the spout D the sleeve B is turned to bring that member into a like relation.

As will be observed, the extremity of the lower container C is contracted into the form of a pipette, as F, the direct passage therethrough being interrupted by a web or partition β . Orifices, as f' f'' , are formed through the wall of said pipette, as seen, being respectively located above and below the web β .

30. The substance or wall of the pipette F is enlarged for a short extent at that portion containing the orifices f' f'' , said enlargement being in the nature of an upward taper or truncated-cone-like formation, its external surface being prepared as a valve-seat, and an annular sleeve G is placed about the pipette F, said sleeve being interiorly shaped and prepared to seat snugly but turnably about the said enlargement while being capable of movement upwardly and incapable of movement downwardly therefrom. Thus it will be noted that the sleeve G, which forms an adjustable closure or stop-cock, is permanently engaged about the apparatus and cannot fall therefrom. Said sleeve G is provided with a handle g , whereby it may be turned, and has an internal vertical recess or groove g' to register with the orifices f' f'' , whereby fluid may pass outwardly through the pipette from container C and whereby said flow may be duly regulated.

It is of course well understood that my improved stop-cocks are equally applicable in regulating the flow of gases as where fluids are employed. As will be also understood, the tubes may be provided with the usual graduated indications, but which it has been deemed unnecessary to illustrate in the drawings.

In an apparatus such as the vertically-disposed tubes shown in the drawings it is evident that the sleeves B or G when raised from their seats and released automatically return thereto by gravity. In some instances I may supplement this operation by the provision of a coiled spring or its equivalent, as indicated

at d in dotted lines, said spring bearing at one end against a stop, as d' , upon the tube A and at its opposite end bearing tensionally against the upper end of sleeve B to positively reseat the closure member. Where the closure to be effected is in a tube or other vessel disposed in a horizontal or inclined plane, the importance of such means for automatically returning the sleeve to its seat will be more apparent.

To permit air to enter the container C when the passage from container A is closed and it is desired to allow a flow through pipette F, I provide an orifice, as c , in the wall of container C and a corresponding orifice, as c' , in the sleeve B, said orifices being capable of registering to provide a continuous passage when the sleeve B is suitably turned.

It is proper to state that when the apparatus is not in use the sleeves B and G are removed from contact with their respective seats and supported in such non-contacting relation by the insertion of a small wad of paper or other object intermediate each sleeve and its seat, the purpose whereof being to prevent adhesion between said members due to the presence of a residuum of the fluid matter passed through the apparatus.

Having now described my invention, I declare that what I claim is—

1. In a receptacle, a stop-cock composed of a member having a passage therethrough and a truncated-cone-like seat, an axially-movable member adapted to fit upon said seat to close, open, and regulate said passage, and means for automatically reseating said movable member when unseated.

2. In a receptacle having an integral, reduced extremity and a truncated-cone-like seat thereon tapering in an opposite direction, an axially-removable sleeve rotatably fitted thereon, and means for automatically reseating said sleeve.

3. In a receptacle, an integral, reduced portion thereof having an external, truncated-cone-like seat, an axially-removable sleeve rotatably fitted thereon and having a corresponding internal surface, an exit in the wall of said receptacle, means in said sleeve for opening, closing, and regulating said exit, and means for automatically reseating said sleeve.

4. In a receptacle, an integral, reduced portion thereof having an external, truncated-cone-like seat, an axially-removable sleeve rotatably fitted thereon and having a corresponding internal surface, a radial arm for turning said sleeve, an exit in the wall of said receptacle, means in said sleeve for opening, closing, and regulating said exit, and means for automatically reseating said sleeve.

5. In a receptacle, an integral, reduced portion thereof having a truncated-cone-like seat, an axially-removable sleeve rotatably fitted thereon and having a corresponding internal surface, an exit in the wall of said receptacle,

means in said sleeve for opening, closing, and regulating said exit, and means for automatically reseating said sleeve.

6. In a receptacle, an integral, reduced portion thereof having a truncated-cone-like seat, an axially-removable sleeve rotatably fitted thereon and having a corresponding internal surface, a radial arm for turning said sleeve, an exit in the wall of said receptacle, means in said sleeve for opening, closing, and regulating said exit, and means for automatically reseating said sleeve.

7. In a receptacle, an integral, reduced portion thereof having a truncated-cone-like seat, an interior, transverse, separating-partition, and orifices through the wall of said receptacle, respectively above and below said partition, together with an axially-removable sleeve rotatably fitted upon said seat, to close said orifices, a vertical groove in the inner surface of said sleeve adapted to align with both said orifices, means for turning said sleeve to bring said groove and orifices into alignment and provide an adjustable passage past said partition, and means for automatically reseating said sleeve.

8. In a receptacle, an integral, reduced portion thereof having a truncated-cone-like seat, an interior, transverse, separating-partition, and orifices through the wall of said receptacle, respectively above and below said partition, together with an axially-removable sleeve rotatably fitted upon said seat, to close said orifices, a vertical groove in the inner surface of said sleeve adapted to align with both said orifices, a radial arm for turning said sleeve

to bring said groove and orifices into alignment and provide an adjustable passage past said partition, and means for automatically reseating said sleeve.

40

9. In a receptacle, an integral, reduced portion thereof having a truncated-cone-like seat, an interior, transverse, separating-partition, and an orifice through the wall of said receptacle, above said partition, together with an axially-removable sleeve rotatably fitted about said seat to close said orifice, said sleeve having an integral spout whose inner end is adapted to align with said orifice, means for turning said sleeve to register said spout and orifice and provide an adjustable exit for said receptacle, and means for automatically reseating said sleeve.

50

10. In a receptacle, an integral, reduced portion thereof continuing into a truncated-cone-like seat portion, an interior, transverse, separating-partition, and an orifice through the wall of said receptacle, above said partition, together with an axially-removable sleeve rotatably fitted about said seat to close said orifice, said sleeve having an integral spout whose inner end is adapted to align with said orifice, a radial arm for turning said sleeve to register said spout and orifice to provide an adjustable exit for said receptacle, and means for automatically reseating said sleeve.
